DESIGN FOR A COMBINED RADIO AND PHONOGRAPH CABINET

Arthur C. Ansley, New York, N. Y.

Application February 7, 1935, Serial No. 55,287

Term of patent 3½ years

To all whom it may concern:

Be it known that I, Arthur C. Ansley, a citizen of the United States, residing at 156 West 20 Street, in the county and city of New York and State of New York, have invented a new, original, and ornamental Design for Combined Radio and Phonograph Cabinets, of which the following is a specification, reference being had to the accompanying drawing, forming part thereof.

The figure is a perspective view of a combined radio and phonograph cabinet, showing my new design.

The right hand side of the cabinet, not shown in the drawing, carries the same small grill shown on the left hand side but does not carry the two arch shape openings on either side of this grill. The back is substantially plain.

I claim:

The ornamental design for a combined radio and phonograph cabinet, as shown and described.

ARTHUR C. ANSLEY.
